UNITED STATES PATENT OFFICE

OWEN A. HAVILL, OF NEW YORK, N. Y., ASSIGNOR TO HANS O. SCHUNDLER, OF NEW YORK, N. Y.

AIRSHIP

Application filed February 4, 1930. Serial No. 425,886.

This invention relates to improvements in airships, and more particularly to a novel aircraft of the dirigible type.

It is well known that aircraft of this character are frequently hundreds of feet in length, and some effort has been made to provide such an airship with a platform to facilitate the launching and landing of aeroplanes on the ship.

10 One of the primary objects of the present invention is to so shape the exterior of the ship so as to make use of substantially the full length of the latter for aeroplane launching and alighting purposes. Due to the special design, the main portion of the bag of the ship, as well as the nose portion of the same, may be utilized to provide a horizontal landing surface which will extend from the extreme nose of the ship to the tail portion of

20 the latter.

Dirigible airships have generally been shaped either circular or elliptical in cross section, and such shape results in rolling of the aircraft. Another object of the present invention is to provide a bag of polygonal shape in cross section, the upper plane surface of which forms an aeroplane launching and landing platform. Another result of this polygonal shape is a safer and more economical airship.

25 A still further object is to combine with the bag of the ship, airfoils which are specially arranged in a staggered formation at each side of the bag, so as not to interfere with one another aerodynamically.

30 Another object is to furnish an airship of this character, in which some of the airfoils carry gondolas which house motors that drive propellers arranged directly beneath the airfoils, so as to protect the propellers from sleet or the like.

35 A further object is to furnish such an airship in which portions of the airfoils, as well as the sides of the bag, are reinforced or provided with armor to prevent any ice thrown by the propellers, from penetrating the airfoils or bag.

40 The improvements forming the subject matter of the present invention are especially

useful with large dirigible aircraft designed to carry heavy loads.

With the foregoing objects outlined and with other objects in view which will appear as the description proceeds, the invention 55 consists in the novel features hereinafter described in detail, illustrated in the accompanying drawings, and more particularly pointed out in the appended claim.

Referring to the drawings,—

Fig. 1 is a top plan view of an airship made in accordance with the present invention.

Fig. 2 is a side elevation of the same.

Fig. 3 is a front elevation thereof.

In the drawings, 4 indicates the bag of the improved ship which is of polygonal cross section throughout its length, the midship cross section preferably having eight plane surfaces, and the bow and stern having four plane surfaces. This configuration permits 70 a horizontal landing platform 5 to extend from the stern 6 to the nose 7 of the ship. To allow for this, the bow has vertical side surfaces 8 which converge forwardly, and which extend from the side edges of the platform 75 to the upwardly and forwardly inclined plane surface 9 of the bow.

This configuration allows a cabin 10 to be arranged directly beneath the landing platform, and permits a car 11 to be positioned 80 directly below the main portion of the bag.

Airfoils 12 project laterally from the opposite sides of the bag, and it will be observed that these airfoils at each side of the bag, are arranged in staggered formation, so that air currents set up by one airfoil will not have any detrimental effect on a following airfoil. Some of the airfoils support gondolas 13, which house engines 14 that are employed in driving propellers 15 which are arranged 90 directly beneath the airfoils, so that they are protected from the weather by such airfoils.

As propellers are prone to accumulate ice in cold damp weather, the portions of the airfoils and bag adjacent to the propellers are 95 armored with sheets 16 and 17, so as to prevent any ice thrown by the propellers from penetrating the airfoils or bag.

The cross sections having the forms of polygons, either regular or irregular, with a 100

small number of sides, in accordance with the present invention, effects a novelty and improvement in airships to the extent that they reduce rolling or sidewise movement, and 5 also pitching or fore and aft tossing, and they enable a stream-line form to be adopted, thereby reducing drag. The mechanical stresses of an airship having this polygonal form of cross section are more exactly determinable than those corresponding to the circular or elliptical form the results of which 10 are simpler and safer structural construction of airships.

Due to the staggered arrangement of the 15 airfoils, we secure a high lift efficiency for the group of airfoils, and in flight, these airfoils will generally provide sufficient lifting power to compensate for their own weight, while at and above half normal speed of the airship, say forty miles per hour or over, they 20 will furnish an excess of lifting capacity beyond that corresponding to their own weight.

These airfoils should be short as compared 25 with their length, and the addition of these airfoils will increase the stability and glidability of the aircraft, and also provide a parachute effect.

By the employment of these airfoils, the 30 ship will be more steady in flight, and will steer and maneuver better, enabling the operators to guide for a comparatively great distance, whereby in emergency, a safe landing place may be picked in the event of 35 accidental loss of lifting gas.

35 In existing airships, the propellers are not sheltered from, but are exposed to depositing of ice from the surrounding atmosphere, missiles from other airships, or materials such as bottles, empty containers, etc., 40 thoughtlessly released by passengers or kitchen personnel. These missiles may damage the propellers, and ice deposited on the latter is usually thrown therefrom into the side of the airship, with dangerous re- 45 sults.

By arranging that the propellers be located under the airfoils, near their trailing edges, the following advantages are effected. The propeller is sheltered from missiles coming from the ship on which they are mounted, or from other neighboring sources. Sleet, 50 ice or the like is less liable to adhere to the propellers, and be then thrown into the side of the airship. All propellers may also be driven mechanically through gears from one or several engines located within the bag of the airship or electrically from a central electric generator situated within the bag.

Furthermore, the shape of the bag of this 60 ship affords a ready means of reinforcing the side of the airship adjacent to the propellers, as shown at 17, so that the bag can withstand the impact of pieces of ice or other materials thrown by the propellers.

65 Rudders 20 aft of some or all propellers

provide for steering the aircraft either as auxiliary steering or entire steering in event of accident to the main rudders, usually located at the stern of aircraft.

From the foregoing it is believed that the 70 construction, operation and advantages of the invention may be readily understood, and we are aware that changes may be made in the details disclosed, without departing from the spirit of the invention, as expressed in 75 the claim.

What I claim and desire to secure by Letters Patent, is:

A lighter than air aircraft comprising an 80 elongated bag of polygonal cross section throughout substantially its entire length and having a plane unobstructed platform along its top extending from the end of its nose toward the trailing end of the bag and forming an aeroplane runway, airfoils 85 extending from opposite sides of the bag, the airfoils being arranged in series at each side of the bag, the airfoils of each series being arranged one behind the other and in staggered formation, gondolas carried by the airfoils, engines housed by the gondolas, propellers driven by the engines and arranged beneath and protected by the airfoils, a main rudder for the bag, and auxiliary rudders positioned rearwardly of the propellers. 90 95

In testimony whereof, I have signed this specification.

OWEN A. HAVILL.
